APPARATUS FOR MAKING SEALING DEVICES

Hans F. Stoffel, Scarsdale, N. Y.

Application February 27, 1946, Serial No. 650,715

7 Claims. (Cl. 113—1)

1

This invention relates to the production of sealing means and more particularly to process and means for continuously manufacturing sealing devices and affixing the same to articles for the purpose of authenticating quality and origin thereof and protecting such articles against tampering.

It is one of the main objects of this invention to provide means offering the possibility of continuously forming sealing devices from flat blank material and of attaching the thus formed devices during the ensuing closing operation to articles to be sealed.

It is another object of this invention to provide means affording the continuous supply of pre-shaped blanks from one station of a machine, then working and transforming said blanks at another station to open, cap-shaped sealing devices, and closing said sealing devices at a final station (by a curling operation) while the same are applied to respective articles to be sealed.

A further object of this invention is to provide means enabling improved and simplified manufacturing steps for obtaining cap-shaped sealing devices, and further means adapted to achieve timed relationship between forming and closing actions on said sealing devices.

Still another object of this invention is to provide means permitting rapid formation of smoothly finished open sealing devices from a stack of sealing blanks carried by a magazine and speedy and secure closure of such sealing devices for application to any desired articles to be protected against tampering, injury, etc.

Yet, a further object of this invention resides in the provision of means effectuating the curling of the rim portion of a sealing device for closing the same and for accommodating therein one or more portions of a cord, string or wire from an article to which said string or wire has been applied.

Still another object of this invention is to provide means contributing to efficient, speedy and uninterrupted operation of the forming and closing implements employed for said sealing devices, the parts of said implements being so arranged and constructed that they only necessitate a minimum of space although these implements comply substantially with all requirements of the practice and permit their handling even by unskilled labor.

A still further object of the present invention is to provide means ensuring smooth working conditions of the synchronized parts of the machine made in accordance with this invention.

2

by which a substantially flat seal blank is subsequently supplied to cooperating dies for forming dish-shaped sealing means devoid of any wrinkles or other uneven surface portions, and then transferred to at least one other die by which the dish-shaped sealing means is further worked upon and closed.

These and other objects and advantages will follow from the ensuing specification and attached drawings illustrating one of many possible embodiments of the invention.

In the drawings:

Fig. 1 is a side-elevational view of a machine (some parts being shown in section, other parts being broken away) for producing sealing devices and embodying the invention.

Fig. 2 is a sectional view taken along line 2—2 of Fig. 1 and disclosing the supply mechanism for seal blanks.

Fig. 3 is a top plan view of the supply mechanism for seal blanks and a further detail for retaining each blank in the machine.

Figs. 4 to 10 illustrate various steps (diagrammatically indicated) of the process of shaping a seal cap from a seal blank and the transformation of the seal cap to a closed sealing device.

Fig. 11 is a fragmentary top plan view of the feeding mechanism with a preshaped seal blank inserted therein.

Fig. 12 illustrates a closed sealing device with a cord enclosed in the curled rim portion thereof, as produced in accordance with this invention.

Referring now particularly to the attached drawings, there are more schematically disclosed in Figs. 1 and 2 the connections between the main parts of a machine by which this invention may be carried into effect.

On base plate 20 of the improved seal forming and closing machine 21, there is supported by means of a suitable bracket (not shown) a shaft 22 which is driven by a motor or similar power means (not shown). Shaft 22 carries a cam 23 which is in engagement with oppositely disposed rollers 24 and 25. Roller 24 is attached to a rocker lever 26 which is pivoted at 27 about an axle 28 extending between standards 29 and 30 which are fixed in any appropriate manner to the machine base 20 (these standards being shown in Fig. 1 broken away).

Roller 25 is mounted on lever 31 at 32, said lever 31 being pivotally supported on a suitable horizontal shaft 33. Lever 31 has a fork-shaped extension 35 forming an integral part of lever 31.

It will be noted from Fig. 1 that rocker lever 26 and lever 31 are interconnected by means of a

coil spring 36 which is anchored and held in position at studs 37 and 38, respectively. Further affixed at stud 37 is another coil spring 40 which extends to an operating linkage device 39 which is secured at 41 to the base 20 of the hollow base frame of the machine 21.

Fixed adjacent lever extension 35 of lever 31 is a cam-shaped part or lobe 42 which coacts with a roller 43 of a reciprocating lever 44 later referred to.

Lever extension 35 has two arms 35a, 35b, respectively, mounted on the ends of a cross block 45, which may be adjusted relatively to shank or rod 46 by means of two pairs of nuts 47 and 48, engaging the threads 49 of rod 46, as is well understood.

Connected with lever extension 35 is further a pusher lever or swinging arm 50 which is attached by screw bolts 52, 53 to an angle piece 51 of lever 31. Arm 50 carries an adjustable abutment 55 fixed to said arm by means of a lock nut 54. The forward and free end 56 of pusher arm 50 is adapted to follow the reciprocating movements of rod 46 (arrow B) through the lever connection 45-35a-35b-35-51-50, lever 31 being actuated and controlled in its movement by the sprung-urged engagement of roller 25 with the cam surface 23a of the revolving cam 23.

As will be apparent from Figs. 1 and 2, rocker lever 26 is operatively connected (by means of eyelets 60, 61 of yoke-shaped end piece 62 and of pin or axle 63) with the head or end piece 64 of a shank or spindle 65 which actuates the upper forming die 67 held in slidable relation to sleeve-shaped holder member 66. This holder member is enabled to swing together with shank 65 and die 67 about axle 63 when arm 50 is pushed against said holder member and overcomes the action of spring 64a which extends between head piece 64 and the end of lever 26 which is positioned adjacent head piece 64.

In alignment with and opposite upper forming die 67 is a lower forming die 68 which is guided for reciprocating motion relatively to a platform 70 within a tubular pad or sleeve member 69. Centrally to and within said die 68 is disposed an ejector piston 71 which is supported by a coil spring 72 housed in a hollow extension of said die 68.

Fixed to base plate 20 in any suitable manner (by welding or bolt and nut connection) is a framework 73 which carries a fulcrum bar 74 and an anvil holding device 75 adapted for cooperation with said upper holder member 66 carrying said die 67. The position of holder member 66 (indicated by dot-dash lines and designated by II) oppositely to said anvil holding device 75 is seen in Fig. 1.

The drawings show a further position of holder member 66 (indicated by dot-dash lines and designated by I) opposite to the lower forming die 68, also illustrated in Fig. 1, whereas the position of holder member 66 (upper and lower parts thereof being broken away), its relation to arm 50 and the coordinated relationship between cam device 23 and levers 26, 31 and 35 are depicted in full lines in Fig. 1.

Cam 23 not only operates levers 26 and 31 and controls their movements, but also times the movements of supply mechanism 80, as will be hereinafter set forth.

Movement to supply mechanism 80 is imparted by rocker lever 26 and spring 40 which engages lever 81 of linkage device 39. Lever 81 is fixed to and connected through pin 82 with lever 83, said

pin 82 being supported in a suitable bearing 84. Rod 85 is linked to the free end of lever 83 and is pivoted at trunnion 86b to control bar 86, whose end piece 86a is swingably supported in a suitable bearing 87 on base plate 20. The opposite end of rod 86 is ball-shaped at 88 and engages a bearing 89 provided in slide 90.

Carried by trunnion 86b is further a tension spring 91 having its end 92 fixed to a suitable standard 93 attached to and extending from base plate 20. On end piece 86a is also anchored one end of a coil spring 94 at 95, said spring extending for fixation into a slot 96 of reciprocating slide 90.

It will be well understood that by movements of rocking lever 26 a tension of the spring 40 is caused which imparts movement to lever 81 in the direction of the arrow, thus actuating rod 85 and control bar 86 against action of spring 91. Thus, bar 86 transmits to slide 90 a to and fro movement in accordance with arrow C. Slide 90 is provided at its forward end with a nose 97 for guiding a seal blank 100 made of any suitable, preferably metallic material and provided with curved notches 98 and 99 (Fig. 11).

Slide or pusher plate 90 is of considerable thickness, as seen in Fig. 4 and as compared with the thickness of each blank with which said pusher plate engages. Pusher plate 90 may therefore be of rigid construction and is suitably supported on a frame 90a, Fig. 2 shows a magazine 101 from which a stack 102 of blanks 100 may be fed successively onto slide 90. As can be further realized from Fig. 2, magazine 101 consists of two upwardly extending round standards 101a, 101b between which the stack 102 of blanks 100 is positioned with notches 98, 99 of blanks 100 in contact with and guided by the opposed inner rounded faces of said standards 101a, 101b. It is well understood that a weight 103 may be placed on stack 102 in order to bring about feeding of seal blanks or disks 100 by gravity in the direction toward slide 90.

As seen in Fig. 4 on an enlarged scale, the lowermost blank 100 furnished through opening 104 of table 70 from magazine 101 is moved laterally in the direction of arrow D toward a cylindrical opening 105 where said blank or disk is clamped against the undersurface of 70 at 70a and 70b by guide member 69 (Figs. 4 and 5).

By means of the power-driven, in the direction A revolving cam 23, lever 31 and through it lever 35 are caused to first move downwardly lower die 68 together with piston 71 (Fig. 4) to a position indicated in Fig. 5. Lower die 68 is provided with an upper beaded edge 68a, as depicted in Figs. 5 to 10.

Figs. 6 and 7 illustrate how the lower die 68 together with piston 71 is then gradually moved upwardly (by the aforesaid cam mechanism) 60 thereby permitting those blank portions of blank 100 positioned at 70a and 70b to slip out between the undersurface of table 70 and upper edge of sleeve member 69, the latter being surrounded by spring 69a which urges said member 69 downwardly and away from table 70. Thus, a cap-shaped sealing device 100a is formed without any wrinkles and which is subsequently guided through opening 105 of table 70 against the upper die 67. Upper die 67 is provided with 65 a recessed, ring-shaped formation 67a which is adapted during reciprocal movement to cooperate with the beaded edge 68a of the lower die so as to shape said blank and to prepare it for the cup formation. Holder 66 consequently retains 70 a by means of the springy fingers 106 and 107 said

cup-shaped device 100a, said fingers releasably gripping rim 100b within the notches 98, 99.

In order to further positively guide rim 100b during the ensuing upward movement of said device 100a, spring-actuated stripper members 108, 109 are arranged on platform 70, which are pivoted at 110 and 111, respectively. Ends 112, 113 are urged apart by means of a spring member 114 (Fig. 3), which is housed in part 114a fixed to platform 70 by a suitable screw bolt 114b. Thus, during upward movement of lower die 68 with piston 71, the forward ends of the stripper members 108, 109 will be urged outwardly in the direction of arrows E to permit passage of rim 100b past the curved stripper members 108, 109 against the action of said spring 114.

The bottom edges of said stripper members 108, 109 which face platform 70 are preferably somewhat curved so as to further ensure smooth guiding of the cup-shaped sealing device or element 100a in its upthrust through opening 105 of platform 70 onto the upper die member 67 within holder 66 (Fig. 9).

As can be seen in Fig. 10, during the upward movement of die member 67 the cap-shaped sealing device gripped at its notches 98, 99 by said springy fingers 106, 107 is thus transferred to and firmly located on holder 66, while piston 71 due to the action of spring 72 still supports and bears against the median portion 115 of cup element 100a until lower die 68 is sufficiently retracted in the direction of arrow F (by means of the above mentioned cam driving mechanism) relatively to said sleeve or guide member 69 and opening 105 in platform 70, as it is clearly indicated by the downwardly moving steps of die member 68 with piston 71 in Figs. 4 and 5.

During the downward movement of lower die member 68 the feeding mechanism 80, as hereinabove described, is set into action to feed the lowermost sealing blank from magazine 101 below opening or passageway 105 of platform 70 (Fig. 5). Subsequently sleeve or guide member 69 is forced against said blank to clamp the same in desired position during the engagement of cam or lobe 42 with roller 43. This engagement is caused by an upward movement of rocking lever 44 about pivot 74a of fulcrum 74 which in turn is yieldingly supported at 74b on bolt 73a. Bolt 73a is fixed to frame 73 (Fig. 1).

Further, during the aforesaid downward movement of lower die member 68, control arm 50 is forced from one extreme position (shown in dot-dash lines and indicated by Ia) to abut with its free end 56 against holder 66 and to swing the same about pin 63 (against action of spring 64a) to another extreme position (shown in dot-dash lines and indicated by IIa) in which holder 66 comes to lie opposite said anvil carrying device 75 (Figs. 1, 4 and 5).

As soon as this position (indicated by II in Fig. 1) of holder 66 is reached, rocker lever 26 is actuated by the engagement of cam 23 with roller 24 and imparts to spindle 65 a downward sliding movement within and relative to holder member 66 (against action of a spring 66a), which is still engaged by the end 56 of arm 50. This downward movement of spindle 65 to which said upper die 67 is connected, effectuates a bearing of the aforesaid median portion 115 of sealing cap device 100a against the upper face 116 of an anvil 117 which is supported by a coil

spring 118 within a housing 119 of said anvil holding device 75.

Anvil holding device 75 has an upper reinforced portion 120 provided with a bore or opening 121, which terminates into a curling bottom die with rounded edge 122. The upwardly extending wall defining bore 121 is lug-shaped at 123, 124 so as to provide clearance space 125 for said springy fingers 107, 108 (which retain sealing device 100a on holder member 66) when said die member 67, which in the ensuing operation functions as a punch, enters and extends into said bore 121 during the aforesaid downward movement of spindle 65.

15 The penetration of punch member 67 into bore 121 causes anvil 117 to recede (in the direction of arrow G) within said housing 119 while said anvil 117 is guided within a narrower bore 121a provided in portion 120 of holder device 75.

20 The space 125 between the lug-shaped wall portions 123, 124 is used to facilitate insertion of a cord or string-like element 126 before punch member 67 with cap-shaped element 100a comes into engagement with anvil 117. This cord in 25 contact with the rounded die or curling edge 122 is then enclosed during the ensuing curling operation of rim portion 100b of element 100a within the inwardly curled rim 100b, as can be more clearly seen in Figs. 5 and 12. ther into the lower portion of housing 140 is adapted to project a piston 146 whose diameter substantially corresponds to and slidingly fits the wall of the cylindrical bore forming said contracted housing portion 141. Piston 146 is connected to rod or spindle 46 by a cylindrical stem or extension 145 whose diameter is somewhat reduced with respect to that of piston 146 so that extension 145 permits in the bore of contracted housing portion 141 for the passage of fluid 137 through channel 139 between reservoir 136 and housing portion 141. Channel 139 is so disposed that it forms a means for levelling the fluid 137 between reservoir 136 and housing 140 and past piston 146 in the position thereof when it projects into the enlarged lower part of housing 140.

Reservoir or container 136 is closed at its top by a hollow lid 147 having a small opening 148 and an upper larger opening 149 so as to provide space for the escape of air from container 136.

Briefly, the operation of the machine hereinabove outlined is as follows:

While a seal blank is furnished from the magazine 101 onto the slide 90 and is then guided along slot 90b (Fig. 4) into the opening 105 of the platform 70, a previously formed, dish-shaped sealing device 100a has been shifted by means of the holder device 66 into aligned position with the anvil holding device 75. All these movements are initiated, followed up and repeated by the cam driving mechanism which is actuated by shaft 22 to which cam 23 is affixed. During the revolutions of cam 23 levers 31 and 26 are so moved and controlled that the supply of seal blanks, as aforesaid, the formation of the dish-shaped seal and its transfer to the anvil are so timed and effectuated, that a continuous operation of the machine is achieved.

In order to provide a braking or damming effect for the swinging die holder 66 relatively to the movements of the swinging arm 50 which is actuated from lever connection 31—35, and in order to further cushion the movements of other machine parts, such as dies, and to bring about resiliency and smoothness during operation of the machine, the aforesaid hydraulic device 135 is alignedly disposed on the machine with spindle or rod 46.

While spindle 46 is moving in upward direction (caused by the aforesaid cam mechanism) piston 146 engageable with reduced opening 141 dams an abrupt upward movement and permits fluid 137 from reservoir 136 to enter through channel 139 the enlarged housing 140. During downward movement of spindle 46, the same is guided in reduced housing opening 141 while the piston 146 and with it extension 145 freely move in fluid 137 contained in housing 140 which fluid escapes past ball 142 through channel 138.

It is well understood that regulation of the position of the set screw 143 will cause a displacement of ball 142 and will consequently permit a change of the fluid flow passing from housing 140 through channel 138 into reservoir 136, whereby a desired braking effect of the moving parts of the machine will be attained.

It is to be noted that withdrawal of the curled and closed cap element 100a from holding device 75 is brought about by spring 118 urging upper part of anvil 117, which works as an ejector, out of the enlarged portion 120, whereby element 100a still in contact with face 116 of anvil 117 is ejected from within the hollow of said enlarged portion 120. During this ejection operation die 67 is then

8 moved by shank 65 and rocker lever 26 through the aforesaid cam action from position II to position I again in alignment with lower die 68.

It can thus be seen that in accordance with this invention there have been provided a method and means for manufacturing from a stack of flat, preshaped seal blanks, dish- or cap-shaped sealing devices which are subsequently transferred and subjected to means for curling and closing said sealing devices.

Having thus described what is claimed as new and desired to be secured by Letters Patent is:

1. In a machine of the character described, the combination of a platform having an opening, supply means for successively delivering substantially flat metallic blanks to said opening, a pair of reciprocable dies disposed for position, respectively, at either end of said opening and shaped to transform each supplied blank in cooperation with said opening to a substantially dish-shaped sealing device, retaining means projecting from one of said dies, means to move the other die through said opening to shape and to transfer said dish-shaped sealing device to said retaining means, a further die positioned adjacent said reciprocable dies, pusher means for moving said one die with said dish-shaped sealing device retained thereby to said further die for coaction therewith, said further die being provided with a rounded edge for curling and closing said sealing device, said supply means and said reciprocable dies being movable relatively to each other, and power driven cam-lever means operatively connected, respectively, to said pusher means, to said supply means and said reciprocable dies for imparting movements to the same in timed relation.

2. In a machine of the character described, the combination of a platform having an opening, supply means for successively delivering substantially flat metallic blanks to said opening, a pair of reciprocable dies movable for position, respectively, above and below said opening and shaped to transform each supplied blank in cooperation with said opening to a substantially dish-shaped sealing device, retaining means associated with one of said dies, means to move the other die through said opening to shape and to transfer said dish-shaped sealing device to said retaining means, a further die positioned adjacent said reciprocable dies, pusher means for moving said one die with said dish-shaped sealing device retained thereby to said further die for coaction therewith, said further die being provided with a rounded edge for curling and closing said sealing device, said supply means and said reciprocable dies being movable relatively to each other, and power driven means operatively connected, respectively, to said pusher means, to said supply means and said reciprocable dies for imparting movements to the same in timed relation.

3. In a machine of the character described, a magazine for holding metallic flat blanks, slidable supply means positioned at one end of said magazine, a platform having an opening, said supply means being arranged to successively deliver said blanks from said magazine and to said opening, a pair of reciprocable dies disposed for position, respectively, above and below said opening and shaped to transform each supplied blank in cooperation with said opening to a substantially dish-shaped sealing device, retaining means associated with one of said dies, means to move the other die through said opening to shape and to thereby transfer said dish-shaped sealing device

to said retaining means, a further die positioned adjacent said reciprocable dies, said one die being arranged for pivotal movement, pusher means to swing said one die with said dish-shaped sealing device retained thereby to said further die for coaction therewith, said further die including a rounded edge for curling and closing said sealing device, said supply means and said reciprocable dies being movable relatively to each other, and power driven means operatively connected, respectively, to said pusher means, to said supply means and said reciprocable dies for imparting movements to the same in timed relation.

4. A machine for manufacturing sealing devices and applying the latter to string means connected to articles to be sealed comprising a magazine for holding a stack of flat seal blanks, a platform having an opening, slide means supplying successively seal blanks from said magazine stack to said platform opening, a pair of reciprocable dies positioned for cooperation with one another, respectively, above and below said platform opening, one of said dies being provided with a beaded edge, the other of said dies being provided with a ring-shaped recess corresponding to and cooperable with said beaded edge, said reciprocable dies in cooperation with said opening being adapted to shape each blank into a cup-shaped sealing device with a downwardly directed rim, means on said other die for retaining said cup-shaped sealing device thereon, a further die positioned adjacent said reciprocable dies, and means for transferring said other die with said cup-shaped sealing device to said further die, said further die coacting with said other die for curling said rim and enclosing said string means in said curled rim.

5. A machine for manufacturing sealing devices and applying the latter to string means connected to articles to be sealed comprising a magazine for holding a stack of flat seal blanks, a platform having an opening, means supplying successively said seal blanks from said magazine to said platform opening, a pair of cooperable dies, upper and lower dies, respectively, positioned above and below said platform opening, said dies being respectively formed so as to transform each seal blank supplied to said opening in cooperation with the latter to a cup-shaped sealing device with a downwardly extending rim, anvil means positioned adjacent to and coacting with one of said dies, means carried by one die for retaining said cup-shaped sealing device thereon, means for transferring said one die with said cup-shaped sealing device to said anvil means, said anvil means being provided with a rounded edge and being cooperable with said one die for curling said rim to close said sealing device and to incorporate in said closed rim said string means upon action of said one die with said anvil means, and a power driven mechanism operatively connected to said supply means and said pair of dies to move the same in timed relation.

6. A machine for manufacturing sealing devices comprising a magazine for holding a stack of flat seal blanks, a platform having an opening, a slide plate arranged for movement between said maga-

zine and said platform therebelow, the thickness of said slide plate being greater than that of each blank, said slide plate being adapted to successively supply seal blanks from said magazine stack to said platform opening, a pair of reciprocable dies positioned for cooperation with one another, respectively, above and below said platform opening, said reciprocable dies being shaped to transform in cooperation with said opening each supplied blank to a substantially cup-shaped sealing device with a downwardly directed rim, one of said dies being provided with retaining means for engagement with said cup-shaped sealing device, further die means positioned adjacent said reciprocable dies, one of said dies being disposed for movement and cooperation with said further die means for curling the rim and closing the respective sealing device, and means for transferring said one die with said cup-shaped sealing device to said further die means.

7. A machine for manufacturing sealing devices comprising a magazine for holding a stack of flat seal blanks, a platform having an opening, a slide plate arranged for movement between said magazine and said platform therebelow, the thickness of said slide plate being greater than that of each blank, said slide plate being movable for successively supplying seal blanks from said magazine stack to said platform opening, a pair of reciprocable dies positioned for cooperation with one another, respectively, above and below said platform opening, said reciprocable dies being shaped to transform each supplied blank in cooperation with said opening to a substantially cup-shaped sealing device with a downwardly directed rim, means on one of said dies for retaining said cup-shaped sealing device thereon, die means positioned adjacent said reciprocable dies, said one die being disposed for movement and cooperation with said adjacent die means for curling the rim and closing the respective sealing device, pusher means for moving said one die together with said cup-shaped sealing device to said die means, and power driven cam-lever means operatively connected, to said pusher means, said slide plate and said reciprocable dies, respectively for imparting movements to the same in timed relation.

HANS F. STOFFEL.
